UNITED STATES PATENT OFFICE.

JAMES J. LAWLER, OF SCRANTON, PENNSYLVANIA, ASSIGNOR TO HIMSELF
AND JAMES M. EVERHART, OF SAME PLACE.

LIGHTING DEVICE.

SPECIFICATION forming part of Letters Patent No. 224,192, dated February 3, 1880.

Application filed July 14, 1879.

To all whom it may concern:

Be it known that I, JAMES J. LAWLER, of Scranton, Lackawanna county, in the State of Pennsylvania, have invented certain new and useful Improvements relating to Gas-Lighting; and I do hereby declare the following to be a full and exact description thereof.

The accompanying drawings form a part of this specification, and represent what I consider the best means of carrying out the invention.

Figure 1 is a vertical section. Fig. 2 represents a face view in elevation with the cap which covers the valve-operating device removed.

The figures represent the novel parts with so much of the ordinary parts as is necessary to indicate their relation thereto.

Similar letters of reference indicate like parts in both the figures.

A is a body of cast metal screwed on the ordinary gas-pipe B, and provided with an upward-extending shield, C, which encompasses and protects a constant jet from the small passage P. This passage is in constant communication with the interior of the gas-pipe B, and the jet therefrom continues to burn under all circumstances, ready to ignite the main jet whenever it shall issue from the lava tip N.

This latter is connected in the usual manner, and adapted to perform its usual functions of discharging gas in a bright flame adapted to produce the desired illumination. A half-way or intermediate small burner is marked m.

E is a conical valve, closing from below, and controlling the flow of gas to the tip N. The valve has a stem, f, which plays through a diaphragm.

I is a spiral spring of gentle force. R is a rocking shaft mounted gas-tight in the casting A, but carefully fitted, so as to turn with moderate force. A portion contiguous to the valve F is cut away, so that when the shaft R is in one position it will leave the valve F free to be closed by the force of the spring I; but when the shaft R is partially turned it will strike the valve F and open it. The protruding end of the shaft R has two rigid arms, R' R². The whole is inclosed in a metal casing, L, with a removable front, M, which protects

it from disturbance and allows examination and lubrication, if desired.

D is a loosely-working piston, having considerable weight, mounted in a vertical cylinder, E, nearly under the arms R' R². 55

W is a rubber bulb, similar to that employed in the Mattson syringe, and w is a tube of rubber or other suitable material communicating therefrom to the space below the piston D.

The arm d extends laterally from the upper 60 edge of the piston through a slot in the cylinder E, and carries a loosely-hinged pusher-piece, which is equipped with a spring, j, which tends to hold it in a vertical position. There are, furthermore, two fixed guides, G' 65 G², which at each descent cause the piece J to assume the correct central position.

The upper end of the piece J is formed with two wide notches, j' j². When the piston D is thrown up by the sudden increase of pressure below it, due to the construction of the bulb W, one arm, R' or R², is carried upward with a curved motion by the piece J, propelled by the arm d. As the piece J rises out of contact with the guide-pieces G' G² one of 75 its notches, j' or j², will receive the corresponding arm, R' or R², and force it upward, thereby rocking the shaft R in one direction.

When the notch j' is engaged with the arm R' it will deflect the push-piece J to the left, 80 and thus cause the push-piece to move entirely clear of the opposite arm, R². On the descending movement the free swiveling of the push-piece J will allow it to move down without effect. On the next rise the notch j² will engage with the arm R², and, raising the latter, will restore the rocking shaft R to its original position. Each elevation of the arm R' liberates the valve F and allows it to rise with the force of the spring I and shut 90 off the gas. The next movement of the piston, by elevating the arm R² and turning the shaft R in the opposite direction, causes the latter to assume a position which holds the valve open. Thus conditioned the gas flows 95 liberally to the main burner N, and causes a strong jet, which being ignited by the small flame from the passage P and m gives the required illumination.

So soon as it shall be desired to extinguish 100

the light another compression of the bulb W causes another sudden elevation of the piston D and push-piece J, which will, by acting with the notch j' and on the arm R', again turn 5 the rocking shaft R into the position for closing, and the main jet will be extinguished.

I have described the small passage P as constantly open. This is true relatively to the alternate letting on and off of the jet from the main burner N. It burns constantly, but with 10 so small a flame that the consumption of gas is insignificant. The shield C performs an important function in protecting this slight flame from being extinguished by accidental 15 causes.

When it is required for any cause to put the burner permanently out of use the screw-plug G is turned inward, and the passage P thereby is closed.

20 The apparatus may be used for lighting the gas in ordinary rooms wherever the burner, by reason of its height or other causes, is difficult of access. It may be made especially useful in sleeping-rooms by placing the bulb 25 W at the head of the bed or other convenient place to allow a light to be made and extinguished in any distant part of the room to determine the time, or for any other purpose, without the necessity of rising or of much exertion.

30 A feature to which I attach much importance is the small burner m midway between the main illuminating-burner N and the small constantly-discharging burner P. This small 35 burner m receives gas as soon as the gas is admitted to the main burner through the pipe B' above the valve F, and by its igniting from the small constantly-burning flame P is sure to light the gas escaping from the main burner 40 N without delay. This half-way burner m may be a sufficiently large file-groove in the side of the nipple of the burner N, or may be made in the upright pipe or burner.

45 Modifications may be made. The apparatus may be used with two or more gas-lights, and

their connections operated from the same pipe W or branches therefrom.

The spring I may be omitted and the device worked with tolerable success with the push-piece J brought into the correct position 50 simply by the guides G' G².

The invention may be worked by a cylinder and piston, a bellows, or other ordinary device for inducing the sudden increase of pressure of the air in place of the hand-bulb W. It 55 may also be worked with iron gas-pipes or other pipes in place of the flexible pipe w. I propose to use it for lighting the lamps of streets, for lighting a whole section of a city or town at once, by a motion communicated from 60 a pressure of air through pipe w, or its equivalent, communicated from a strong hand or power device at the central office.

I claim as my invention—

1. In combination with a main gas-tip, N, 65 and small constantly-burning jet P, the pipe w, with means for communicating changes in the pressure of air from a distant point, and a valve-operating device, R R' R², with devices for causing it to be turned alternately in opposite directions by the successive compressions of the air, as herein specified.

2. In combination with the main burner N and small igniting-jet P, the shaft R, with its arms R' R², arranged as shown relatively to 75 the piston D, and loosely-hinged piece J, and means w W for inducing changes in the pressure of air from a distant point, as herein specified.

3. In combination with a main gas-tip, N, 80 and small constant burner P, the intermediate burner, m, as and for the purpose herein specified.

In testimony whereof I have hereunto set my hand this 10th day of July, 1879, in the 85 presence of two subscribing witnesses.

JAMES J. LAWLER.
